UNITED STATES PATENT OFFICE.

GEORGES ERNEST RAINAUD, OF VINCENNES, FRANCE.

BOX FOR ILLUMINATED SIGNS AND TRANSPARENCIES.

No. 845,478.

Specification of Letters Patent.

Patented Feb. 26, 1907.

Application filed September 28, 1905. Serial No. 280,119.

To all whom it may concern:

Be it known that I, GEORGES ERNEST RAINAUD, a citizen of the Republic of France, residing at 44 Rue du Plateau, Vincennes, 5 Seine, in the French Republic, commercial traveler, has invented certain new and useful Improvements in or Relating to Boxes for Illuminated Signs and Transparencies, of which the following is a specification.

Boxés of the type herein described (intended to receive any arrangement whatever for illuminating) have up to the present time at least one of their faces made of a plate of which the front side exhibits transparent objects in relief consisting of letters or other designs, &c. These objects in relief have at their backs corresponding with the back of the plate spaces or chambers in direct communication with the interior of the box. 15 Under such construction water, dust, vapor, smoke, &c., proceeding from the interior of the box penetrate to the spaces or chambers and lodge therein, causing a very considerable diminution of the transparency of the 20 parts in relief. For this reason it is frequently necessary to dismount the apparatus to clean the chambered parts, which is a notable inconvenience.

According to the present invention the 30 chambered pieces or parts are protected against direct communication with the interior of the box; in consequence of which all dirt or other accumulations therein are prevented. This result is accomplished by the 35 interposition of a supporting-plate between the interior of the box and the designs in relief.

The accompanying drawings illustrate means for accomplishing the object of the invention.

Figure 1 is a front elevation. Fig. 2 is an edge view, Fig. 3 a longitudinal sectional view, and Fig. 4 a rear elevation, of a letter ready for application. Fig. 5 is a front 45 elevation, and Fig. 6 a corresponding edge view, of a supporting-plate for receiving the letter shown in Figs. 1 to 4. Fig. 7 is a front elevation showing the letter applied on the supporting-plate, and Fig. 8 is a longitudinal 50 section corresponding with Fig. 7. Fig. 9 is a front elevation showing a series of letters applied on one supporting-plate. Fig. 10 is a plan view, with parts in section, showing a box of which one of the faces is composed of a 55 plate corresponding with that shown in Fig. 9.

The letter for application (represented at Figs. 1 to 4) comprises a plate 1, of which the front face presents some portions in relief, forming the letter H. Corresponding with the parts in relief are hollows or cavities on 60 the back of the plate.

In plate 1 are shown two holes 2 and 3 to assist in fixing the letter upon the supporting-plate represented in Fig. 5 and 6. The supporting-plate, Figs. 5 and 6, is likewise 65 provided with two holes 4 and 5, corresponding exactly with holes 2 and 3. On Fig. 5 the position which the applied letter will occupy is traced by a dotted line. The supporting-plate 6 is, by preference, made of 70 transparent material rendered opaque by any convenient means—for example, by the application of a mass of color extending to the hatched portion, which should be left transparent to allow the light-rays to pass 75 through to make the letter appear luminous.

As shown in Figs. 7 and 8, the applied letter is placed upon the supporting-plate 6 under the predetermined arrangement and in such manner that the holes 2 and 3 correspond with those at 4 and 5, and through 80 these holes are passed bolts 7 and 8, the proper pressure being secured by nuts, as 9 and 10. In addition elastic washers 11 and 12 are placed upon the bolts in such manner 85 as to lie between the two united parts or pieces and to facilitate the tightening.

The arrangement described indicates only the union of a single letter with a supporting-plate suitable for receiving but one letter. 90 In that case the supporting-plate 6 will constitute one of the faces of a box suitably equipped within for receiving the selected illuminating apparatus—electrical, for example—in such manner that the assemblage 95 of this box, the supporting-plate, and the applied letter constitutes a box for a single letter. A luminous sign in such case will be made up by a number of similar boxes, according to the number of letters in the sign. 100

I may install also a collection of applied letters upon a single supporting-plate. This is indicated in Fig. 9. The mounting is effected as in the case of a single letter so far as the union of the transparent piece 6 to the 105 box 13 is concerned, as indicated in Fig. 10. In this figure the box is represented in section, so as to show the manner in which the plate 6 is maintained. Upon the left-hand side of this Fig. 10 is represented an arrange- 110

ment for holding the plate in a groove, while upon the right-hand side is represented another manner of securing the same object by means of a bolt and nut.

5 In Fig. 9 the hatch-lines show the portions which will be illuminated—that is to say, the raised portions of the letters—all the other portions of the surface of the transparent plate 6 being rendered opaque by any appropriate means.

Having now fully described my invention, what I claim as new herein, and desire to secure by Letters Patent, is—

1. A box for signs and luminous transparencies having one or more transparent designs in relief upon the front face and hollow upon the back, one of the faces of the box consisting of a supporting-plate of glass upon the front face of which the back faces of the 15 designs are fixed to prevent admission of foreign matters to the hollow portions of the designs, the portions of the supporting-plate not covered by the affixed designs being rendered opaque and the portions covered by 20 said designs being left transparent, the parts being combined substantially as shown and described.

2. In a box for signs and luminous transparencies having one or more designs in relief upon the front face and hollow upon the 25

back, one of the faces of the box consisting of a supporting-plate upon the front face of which the back faces of the designs are fixed to prevent admission of foreign matters to the hollow portions of the designs, the combination with the supporting-plate of bolts passing through holes provided in the designs and through corresponding holes in the supporting-plate, and nuts applied upon the inner ends of the said bolts. 35

3. In a box for signs and luminous transparencies having one or more designs in relief upon the front face and hollow upon the back, one of the faces of the box consisting of a supporting-plate upon the front face of 40 which the designs are fixed to prevent admission of foreign matters to the hollow portions of the designs, the combination with the supporting-plate of bolts passing through holes in said plate and in said designs, nuts upon 45 the inner ends of the bolts and elastic washers upon the bolts and between the designs and the supporting-plate. 50

In testimony whereof I have hereunto set my hand, in presence of two subscribing witnesses, this 14th day of September, 1905. 55

GEORGES ERNEST RAINAUD.
